UNITED STATES PATENT OFFICE.

FREDERICK J. MITCHELL AND OLIVER B. WARREN, OF NEW YORK, N. Y.

APPARATUS FOR SUPPLYING HYDROCARBON AND OTHER LIQUIDS FOR LIGHTING, &c.

SPECIFICATION forming part of Letters Patent No. 369,870, dated September 13, 1887.

Application filed January 28, 1886. Serial No. 190,031. (No model.)

To all whom it may concern:

Be it known that we, FREDERICK J. MITCHELL, a subject of the Queen of Great Britain, and OLIVER B. WARREN, a citizen of the 5 United States, both residing at No. 453 West Thirtieth street, in the city of New York, have invented a new and useful Apparatus for Supplying Hydrocarbons for Lighting and Heating, of which the following is a specification.

10 The objects of our invention are to secure greater safety in the use of hydrocarbons and other liquids used for lighting or heating, economy in such use, more perfect combustion, and certainty of supply. We attain 15 these objects by the aid of the mechanism illustrated in the accompanying drawings, in which—

Figure 1 is a vertical section of the entire apparatus, and Fig. 2 a vertical section of the 20 governing device.

Similar letters refer to similar parts in the two views.

Our method of supply is adapted to the use of any liquid used for artificial lighting; but 25 as the liquid most largely used is commonly classed as an "oil," we shall use the term "oil" in our description for the sake of perspicuity.

In Fig. 1, A is a reservoir, which is partially or completely filled with any hydrocarbon or other liquid used for illuminating or heating. This reservoir A is connected by the pipe B with the governing apparatus C, which apparatus is more fully shown in Fig. 30 2. The pipe D connects the governor C with the reservoir E. The pipe F F F, a siphon in form of construction, extends from the governor C to the pendant, which may be constructed with a vertical tube, H, hollow arms 35 I I, and chambers K K. These chambers are supplied with a burner and wick, which may be of any suitable pattern or kind. The reservoir A, Fig. 1, is placed in any convenient position above the level of the governor C, 40 and filled with oil to the height shown by the dotted line a a. The oil descends by its own gravity through the pipe B into and fills the containing-case b b b of the governor C, passing through the valve-chamber J.

45 The construction of the governor C is more fully shown in Fig. 2, in which b b b is the containing-case, in the bottom of which a de-

pression or well, d, is formed. To the bottom of the case b b b is secured the valve-chamber J, to the outer end of which the pipe B is connected. A float, L, is placed within the case b b b. To this float L the arm M is rigidly fastened at m, the other extremity of the arm M being hinged to the support N at n. This construction permits a vertical movement of 50 the float L. The valve-chamber J is formed with an upper and lower seat, into which the double-faced valve O is seated when actuated by the movement of the float L through the medium of a prolongation of the valve-stem 55 P and its connection with the arm M at o. At the upper part of the case b b b, and above the line l l, the pipe D is connected, extending down into the reservoir E. (Shown in Fig. 1.)

As before stated, the oil contained in the 70 reservoir A descends by its own gravity through the pipe B into the case b b b of the governor C. This causes the float L to rise. By proper adjustment of the length of the valve-stem P, when the oil has reached the 75 level l l, the upward movement of the float L brings the valve O firmly against the upper seat of the valve-chamber J, preventing a further inflow of oil as long as there remains sufficient oil in the case b b b to support the 80 float L.

The pipe F F F, supported in any convenient position, is constructed upon the principle of the siphon, the legs being of equal lengths. The leg f is inserted in the case of 85 the governor C, extending down into the well d, and fixed in such a position that the open end of the leg f is within a short distance of the bottom of the well d. The leg g of the siphon F F F is constructed so as to extend 90 down through the tube H of the pendant, and is fixed in such a position that the open end of the leg g is within a short distance of the bottom of the well G. The length or drop of the pendant is adjusted to bring a point in the 95 chambers K K (which point is below the burners) upon the same level as that of the oil in the governor C. This level is shown by the dotted line l l. The chambers K K and the hollow arms I I are filled with oil to the 100 level l l, and the siphon-pipe F F F charged with oil in any manner that will completely fill it and exclude the air.

It will be seen that we have provided two

receptacles for the oil placed upon the same level, but at a distance from each other, and connected by a siphon. A change in the level of the oil in one receptacle—for example, the 5 chamber K—will be followed by a change in the level of the oil in the other receptacle—for example, the containing-case of the governor C. The wicks of the burners being ignited, a portion of the oil is drawn from the 10 chambers K K, lowering the level of the oil therein, and increasing the length of the leg g of the siphon F F F. Following the known natural law governing a siphon a movement 15 of the oil in the siphon F F F takes place, drawing from the supply in the containing-case of the governor C. This results in a lowering of the level of the oil in the governor C, a consequent falling of the float L, the opening 20 of the valve O, and the admission of a supply of oil to the case of the governor C through the valve-chamber J and the pipe B from the reservoir A.

In practical operation it has been demonstrated that the valve O is automatically adjusted by the movement of the float L to a position admitting of the passage of just sufficient oil to supply the consumption at the burners, and is maintained in that position as long as the demand is unchanged.

30 If the valve O from any cause is prevented from performing the office of closing the passage from the reservoir A to the governor C, and consequently the level of the oil in the governor C is raised above the line l l, an 35 overflow is prevented by the action of the pipe D, which conducts the surplus oil into the reservoir E. A device operating in the same manner can be supplied to the pendant.

The reservoir A, the governor C, and the 40 reservoir E may be placed outside of the apartments or building where used.

A rupture of the pipe F F F from any cause—as from fire or accidental breakage—results in the immediate flow of oil away from the point 45 of rupture, descending on the one side into the case of the governor C, and through the overflow-pipe D into the reservoir E, and on the other side into the overflow-receptacle which may be provided in the pendant, such rupture

of the pipe F F F destroying the vacuum that 50 had previously been maintained therein.

We find by practical tests that the chambers K K, and all other parts of a pendant for three burners, together with twenty lineal feet of pipe, may be constructed of such sizes as to 55 contain less than one pint of oil. As the oil is maintained at the same level, the height of the burners can be fixed at that point which will insure the most perfect combustion. The 60 burners being so placed, their temperature is maintained by the constant flow of cool oil from the reservoir below the point at which undue vaporization of the oil takes place and the consequent escape of noxious foul-smelling gases which vitiate the surrounding air. 65

We are well acquainted with the fact of the prior use of floats for the control of valves for regulating the flow of liquids, and to that portion of the apparatus described we make no claim; but

What we do claim as our invention, and desire to secure by Letters Patent, is—

1. The combination of the reservoir A, siphon-pipe F F F, governor C, and the pendant having a vertical tube, H, hollow arms I I, 75 chambers K K, and well G, substantially as shown and described.

2. The reservoir A, governor C, having containing-case b b b, well d in its bottom, for the reception of the siphon-pipe, overflow-pipe D, 80 valve-chamber J, valve-stem P, valve O, the float L, for operating said valve, and the pendant having well G, substantially as shown and described.

3. The combination of the reservoir A, pipe 85 B, governor C, having containing-case b b b, well d, overflow-pipe D, leading to the reservoir E, valve O, means for operating said valve, float L, the pendant having the well G, and siphon-pipe F F F, connecting governor and 90 the well G, substantially as shown and described.
